CARLOS A. SMITH, OF BELLAIRE, OHIO.

LAUNDRY IRONING OR PRESSING MACHINE.

1,007,148.

Specification of Letters Patent. Patented Oct. 31, 1911.

Application filed April 26, 1910. Serial No. 557,811.

To all whom it may concern:

Be it known that I, CARLOS A. SMITH, a citizen of the United States of America, and resident of Bellaire, county of Belmont, and 5 State of Ohio, have invented certain new and useful Improvements in Laundry Ironing or Pressing Machines, of which the following is a specification.

This invention relates to improvements in 10 laundry ironing or pressing machines, and more particularly to that class of machines known as flat-work pressing machines; and it consists in the particular construction, arrangement and combination of parts which 15 will hereinafter be fully described.

The primary object of the invention is to provide a machine whereon large flat pieces, such as bed-sheets, table cloths, and the like, may be accurately placed, or "squared", 20 prior to the pressing operation, and which will consequently effect the pressing in such manner as to leave the pressed articles regular in form or shape.

Further important objects of the invention will hereinafter become apparent as the 25 nature of the same is more fully understood.

In describing the invention in detail, reference is herein had to the accompanying drawings, forming a part of this specification, in which—

Figure 1 is a top plan view of the invention; Fig. 2 is a side elevation of the same; Fig. 3 is an enlarged front end-elevation of 35 a broken portion of the machine, showing the gearing; Fig. 4 is a central longitudinal section of the same; Fig. 5 is an enlarged front elevation of the clutch employed in operating the pressing table or chest and the controlling mechanism therefor, other 40 portions of the mechanism being removed for the sake of clearness; Fig. 6 is a similar view of the same occupying a different position in its operation; Fig. 7 is an enlarged partial section on the line 7—7, Fig. 1, showing 45 portions of the table elevating mechanism; Fig. 8 is a similar view of a portion of the front end of the machine, showing parts occupying different positions from those shown in Fig. 7; Fig. 9 is a top plan 50 view of a broken portion of the machine, showing the clutch employed in advancing the apron and illustrating portions of the clutch operating mechanism; Fig. 10 is a detail view showing the link mechanism; 55 and Fig. 11 is an enlarged cross section on

the line 11—11, Fig. 1, showing the lateral work-gripping device carried by the pressing table.

Referring to said drawings, in which like designating characters distinguish like parts throughout the several views—1 indicates the sides of a frame which supports at the rear end thereof a stationary bed 2 of any suitable or appropriate type or character having a flat upper surface. Journaled in each of the opposite ends of said frame is a cylindrical roller 3, said rollers being connected by an endless apron 4 adapted to carry the work to be acted upon, the upper lap of said apron traveling over the surface 70 of the table 2. A vertical-adjustable roller 5, by means of which the tension of the apron may be adjusted, is mounted in an appropriate position in the lower part of the frame, and one or more apron-supporting rollers 6 are mounted in the upper part of the frame in the rear of the table 2, as shown. Journaled in the frame in an appropriate position is a drive-shaft 7 which is connected by belt, chain, or otherwise, (a 80 chain 8 being herein shown) to an actuating member for a roller 9 which is geared to the roller 3 at the rear or table-end of the frame for driving the same to carry the apron.

While any approved suitable motive power and gearing may be employed for driving the machine, that herein shown is preferred and, in part, comprises a motor 10 whose drive-shaft carries a worm 11 in mesh 90 with a worm-gear 12 loosely mounted on the drive-shaft 7 of the machine, a sprocket-wheel 13 bolted to said worm-gear through space-blocks 14 so as to turn with said worm-gear, a sprocket-wheel 15 rotatably mounted 95 on the shaft 16 on which the roller 9 is fixed, said sprocket chain 8 connecting said sprocket-wheels, and meshing gear-wheels 17 and 18 respectively fixed on the necks of the rollers 9 and 3.

Located directly over the bed 2 is a vertically-movable pressing table, designated in a general way by the numeral 19, which is adapted to be reciprocated with relation to said bed for pressing articles advanced over the latter by the apron 4. Said table 19 comprises, essentially, a heated chest 20 to which or through which steam, heated air, or hot water is passed, as through suitable flexible valve-controlled tubes 21 leading 110

into the chest. Said pressing table or chest is supported by four trunnions 22 directed outwardly therefrom, each trunnion being loosely mounted in a lever 23 at a point intermediate the ends of the latter. The two 5 levers 23 at each side of the chest are pivotally mounted at their outer ends in upright portions 24 of the frame 1, and at their inner, or adjacent, ends to the upper ends of links 25 whose lower ends are pivotally connected to the opposite ends of a cross-head 26, adjustably mounted upon a vertically movable rod 27, the operation of which will presently be explained.

15 A treadle 28 is arranged in a position parallel to the frame at the front end of the table so as to be convenient to the operator when placing or adjusting the work on the apron. Said treadle is mounted at its opposite ends upon outwardly-directed arms 29 carried by a longitudinally extending shaft 30 which is loosely mounted in one side of the frame. Pivotally connected to said treadle, so as to be drawn downward 20 when the latter is depressed, is a substantially upright rod 31 whose opposite end is pivotally connected to one arm of a bell-crank 32, the opposite arm of which has a hook 33 formed thereon adapted for interlocking engagement with a lip 34 carried by a vertically movable rod 35 which is mounted in outwardly-directed vertically-aligned arms 36 carried by the frame, as shown in Figs. 5 and 6. Interposed between 25 the upper of said arms 36 and an adjusting nut 37 carried upon the upper threaded end of said rod 35 is a rod-encircling coil-spring 38 adapted for normally maintaining said rod in an elevated position, as shown in Fig. 6. Pivotally connected to the upper 30 end of said rod 35 is an angular hand lever 39, one end of which is fixed upon a shaft 40 extending transversely of, and journaled in the opposite sides of, the frame. And fixed 45 upon said shaft 40 at points adjacent to the opposite ends of the latter are the terminal members 41 of a transverse bar 42, the body of which is adapted to be clamped upon the previously stretched and straightened front 50 end of an article to be pressed placed upon the apron 4, said bar 42 coöperating with a transverse bar 43, underlying said apron and fixed on the frame, to firmly hold the article while the body of the latter is being 55 stretched and straightened prior to the pressing operation. As is obvious, the hand-lever 39 is rocked rearward to the position shown in dotted lines in Fig. 2 to effect the clamping of the front end of the article, and this operation of the hand-lever is 60 effected against the tension of the spring 38, the rod 35 being thereby depressed to a position where the lip 34 is engaged by the hook 33 of the bell-crank 32, a spring 44 65 serving to normally maintain said bell-

crank in an inwardly-drawn, or lip-engaging, position.

Connected with the treadle 28, so as to be operated by depression of the latter, is mechanism for releasing a spring-controlled clutch-member 45, feathered upon drive-shaft 7, to cause the projections 46 of said member to engage or interlock with the hub 47 of the constantly-driven worm-gear 12 and to thus effect the rotation of said drive-shaft. Said releasing mechanism comprises an inwardly and upwardly inclined arm 48 fixed upon the longitudinally-extending shaft 30, said arm 48 having pivotally connected thereto the lower end of an inclined rod 49 whose opposite end is pivotally connected to the free end of an arm 50 fixed upon a shaft 51 extending parallel to the frame and journaled at one end in an outwardly-extended arm 52 and at its other end in the divided arm of a spider 53 in which the outer end of drive-shaft 7 is supported or journaled, the legs of said spider being mounted upon the outer ends of supporting arms 54 carried by the frame. Fixed upon said shaft 51 between the members of said divided arm of the spider, as shown in Fig. 2, is one end of a curved member 55, the downturned free end of which bears an anti-friction roller 56 which is adapted to operate against the vertical cam-faces 57 of the clutch-member 45, hereinbefore referred to, for normally maintaining the latter, against the tension of its thrust-springs 58, in a retracted non-operative position, as is clearly shown in Fig. 5.

When the treadle 28 is depressed, two results are accomplished, the first being the withdrawal of the hook 33 from interlocking engagement with the lip 34, allowing the rod-encircling spring 38 to elevate the lever 39 which, in turn, elevates the work-gripping bar 42. The second result accomplished is the elevation, through the intermediate mechanism, of the free end of the member 55 from the position shown in Fig. 5 to that shown in Fig. 6, releasing the clutch 45 and allowing the springs 58 to thrust said clutch 45 inward into operative interlocking relation with the constantly-moving worm-gear 12. Having assumed such relation, the drive-shaft 7 is actuated to rotate. The foot of the operator is immediately removed from the treadle after the latter has been depressed, and this allows the free end of the member 55 to drop back upon the periphery of the clutch 45. As said clutch rotates, the roller 56 is engaged by a vertical cam-face 57 on said clutch and the latter is thereby withdrawn, 115 against the tension of the springs 58, from operative engagement with the worm-gear 12, stopping the drive-shaft 7. It will be noted that two cam faces are provided on said clutch 45, means being thus provided 120

70

whereby only one-half revolution will be made by said clutch and, consequently, by said drive shaft at a time. Assuming that the pressing table occupied a lowered, or 5 pressing, position prior to the depression of the treadle, when the drive-shaft is given the one-half revolution, as described, an eccentric disk 59 fixed upon said shaft close to the frame is given a half turn, effecting 10 the elevation of said table. Said eccentric 59 operates in an oblong channel or opening 60 in an elliptical member 61 carried by the vertically-movable rod 27, and, when given the half revolution, as above mentioned, 15 thrusts said rod 27 upward, as is clearly illustrated in Fig. 7. The table remains in this upraised position until the drive-shaft is again actuated to make another half revolution. 20 A depending lever 62 is carried by the outwardly-extended end of the pivot-pin 63 upon which is mounted the foremost lever 23 at the gearing-side of the machine, and rotates with said pivot-pin. As the table 25 is elevated, as above described, said lever 62 is swung rearward from the position indicated by dotted lines in Fig. 7 to that indicated in full lines in said figure. In its said movement, it engages a lip 64 carried by a 30 longitudinally-movable bar 65 which is slidably mounted in outstanding arms 66 carried by the frame, and carries said bar rearward therewith against the tension of a suitably mounted spring 67, withdrawing the 35 front end of said bar from engagement with the cam-face 68 of a clutch member 69 feathered on the shaft 16 upon which the roller 9 is rigidly mounted. The withdrawal of said bar releases said clutch 69 which is 40 then immediately thrust outward by springs 70, causing its projections 71 to enter recesses in the hub of sprocket-wheel 15, interlocking said sprocket-wheel with roller 9, and thus effecting the rotation of the rollers 45 9 and 3 which respectively bear on their necks the intermeshing gears 17 and 18. Consequently, it will be seen that, at the same time that the pressing table is elevated, as hereinbefore described, the apron-carrying roller 3 at the front end of the machine 50 is caused to rotate, advancing the apron 4.

Located directly over and parallel to bar 65 is a suitably mounted adjustable stationary bar 72 which has on its outer face 55 an inclined swell 73 over which the lever 62 rides in its said rearward movement. This swell is so located that, when the bar 65 has been moved rearward a sufficient distance to withdraw its end from interlocking engagement with clutch 69, the lever 62 is automatically disengaged from the lip 64, allowing said bar 65 to be again forced forward, actuated by its spring 67. As said clutch 69 rotates, the end of the bar 65 is engaged by 60 the cam-face of the former and said clutch 65

is thereby gradually withdrawn, against the tension of its thrust springs 70, from operative engagement with the sprocket-wheel 15, stopping the advancing movement of the apron 4. A complete revolution of the roller 70 9 is made each time that it is actuated to rotate, as just described; and the gears 17 and 18 respectively carried by said roller 9 and the roller 3 are so proportioned in size that, in a revolution of the former, the apron is 75 advanced a distance just sufficient to carry an article mounted thereon from its initial mounting position at the front end of the machine to a position directly underneath the pressing table. 80

A work gripping device comprising a rectangular member 74 surrounds the pressing table. As shown in Fig. 11, said member is supported upon the lower ends of bolts or screws 75 which are mounted in a vertical 85 position in outwardly-directed supporting-arms 76 carried by said table. Said member 74 normally stands in a position where its lower or gripping face occupies a lower level than the plane of the under face of the 90 table, so that it grips the lateral edges of a rectangular article to be acted upon slightly in advance of the seating of the table when the latter is being lowered. Coil springs 77 interposed between said member 74 and the 95 under sides of the supporting arms 76, and encircling the bolts 75, serve to admit of the table being depressed upon the bed and also cause said member to maintain a grip upon the lateral edges of the pressed article after 100 the table has been slightly elevated, thus effecting the stripping of said article from the pressing face of the table in cases where said article adheres to said face after the pressing operation. 105

To provide for the elevation and depression of the table at a single operation, when such is desired, thereby avoiding the necessity for depressing the treadle to effect each separate movement of the table, a link 110 mechanism is provided between the end of the shaft 16 and the head 78 in which the thrust-springs 58 are mounted. Said mechanism comprises a bell-crank 79 pivotally mounted on an arm 80 carried by said head 78, a spring-pressed dog 81 carried by one arm of said bell-crank and normally underlying the body of the member 55, as shown in Figs. 3 and 10, and a rod 82 pivotally connected at one end to the opposite arm of said bell-crank and at its opposite end to a wrist-pin 83 carried by the end of shaft 16. Now, as will be obvious, assuming that the table is being elevated, when the shaft 115 16 has made a half revolution, the parts constituting the link mechanism above described will be moved from the positions shown in full lines in Fig. 10 to that shown in dotted lines in said figure, elevating said member 55 and thereby releasing clutch 45, 120

13

precisely as when the treadle is depressed, effecting the return, or lowering of the table. The dog is withdrawn from engagement with said member 55 after the latter has been sufficiently elevated, allowing it to drop back to its normal position. As the shaft 16 completes its revolution, the bell-crank 79 is rocked back. When the beveled point of the dog engages the member 55, said dog is forced back against the tension of its spring 84 until it has passed by said member, after which it is thrust outward into a position underlying said member. When it is desired to stop the pressing table at the limit of its upward movement, the hook-end 85 of the rod 82 is disengaged from the wrist-pin 83.

It will be obvious that various alterations may be made in the construction and arrangement of many of the parts without departing from the spirit and scope of the invention as defined in the appended claims.

Having thus described my invention, what I claim as new, and desire to secure by Letters Patent, is—

1. In a laundry pressing machine, a bed, a pressing table located over said bed, a normally stationary shaft, a constantly-driven element rotating on said shaft, means for interlocking said element with said shaft, means interposed between said shaft and said table whereby a complete reciprocation of said table is effected with each revolution of said shaft, automatic means for disconnecting said shaft from said element at each half revolution, a conveyer arranged to travel between the bed and the table, means for advancing said conveyer, and means operated by the reciprocating movement of the table whereby said advancing means is actuated to give the conveyer a definite movement.

2. In a laundry pressing machine, a bed, a pressing table located over said bed, a normally stationary shaft, a constantly-driven element rotating on said shaft, means for interlocking said element with said shaft, means interposed between said shaft and said table whereby said table is reciprocated, means for disconnecting said shaft from said element at predetermined points in the revolution, a conveyer arranged to travel between the bed and the table, and means for intermittently advancing said conveyer.

3. In a laundry pressing machine, a bed, a pressing table located over said bed, a normally stationary shaft, a constantly-driven element rotating on said shaft, means for interlocking said element with said shaft, means interposed between said shaft and said table whereby said table is reciprocated, means for disconnecting said shaft from said element at predetermined points in the revolution, a conveyer arranged to travel between the bed and the table, and means oper-

ated by the reciprocating movement of the table whereby the travel of the conveyer is definitely limited.

4. In a laundry pressing machine, a frame, a bed at one end of said frame, a pressing table located over said bed, a conveyer arranged to travel between said bed and said table, a normally stationary shaft, a constantly-driven element rotating on said shaft, a treadle, means interposed between said treadle and said element whereby said shaft is interlocked with the latter, means actuated by the rotating shaft whereby said conveyer is advanced a definite distance, means actuated by the rotating shaft whereby said table is reciprocated, and automatic means whereby said shaft is disconnected from said element at determined intervals.

5. In a laundry pressing machine, a bed, pivoted levers at opposite sides of said bed, a pressing table located over said bed, trunnions carried by said table, said trunnions being mounted in said levers, a normally stationary shaft, a constantly-driven element rotating on said shaft, means for interlocking said element with said shaft, and means interposed between said shaft and said levers whereby the latter are actuated to elevate and lower said table.

6. In a laundry pressing machine, a bed, pivoted levers at opposite sides of said bed, a pressing table located over said bed, trunnions carried by said table, said trunnions being mounted in said levers, a normally stationary shaft, a constantly-driven element rotating on said shaft, means for interlocking said element with said shaft, vertical rods connected to said levers, and means controlled by movement of said shaft for reciprocating said rods to effect the reciprocation of said table.

7. In a laundry pressing machine, a bed, pivoted levers at opposite sides of said bed, a pressing table located over said bed, trunnions carried by said table, said trunnions being mounted in said levers, a normally stationary shaft, a constantly-driven element rotating on said shaft, means for interlocking said element with said shaft, means interposed between said shaft and said levers whereby the latter are actuated to elevate and lower said table, and means for disconnecting said shaft from said element at predetermined points in the revolution.

8. In a laundry pressing machine, a bed, pivoted levers at opposite sides of said bed, a pressing table located over said bed, trunnions carried by said table, said trunnions being mounted in said levers, a normally stationary shaft, a constantly-driven element rotating on said shaft, means for interlocking said element with said shaft, means interposed between said shaft and said levers whereby the latter are actuated to elevate and lower said table, a conveyer ar-

ranged to travel between the bed and the table, and means for intermittently advancing said conveyer.

9. In a laundry pressing machine, a bed, 5 pivoted levers at opposite sides of said bed, a pressing table located over said bed, trunnions carried by said table, said trunnions being mounted in said levers, a normally stationary shaft, a constantly-driven element rotating on said shaft, means for interlocking said element with said shaft, means interposed between said shaft and said levers whereby the latter are actuated to elevate and lower said table, means for disconnecting said shaft from said element at predetermined points in the revolution, and means under the control of said levers whereby said shaft is disconnected from said element when the table has reached the limit 15 of its reciprocating movement.
10. In a laundry pressing machine, a bed, a conveyer arranged to travel intermittently over said bed, a pressing table located over said bed, means for reciprocating said table 20 with relation to said bed for pressing articles carried by said conveyer, and means carried by said table whereby pressed articles are automatically stripped from the face of said table when the latter is elevated.

11. In a laundry pressing machine, a bed, 30 a conveyer arranged to travel intermittently over said bed, a pressing table located over said bed, means for reciprocating said table with relation to said bed for pressing articles carried by said conveyer, and a work 35 gripping device carried by said table whereby pressed articles are stripped from the pressing face of said table when the latter is elevated.

12. In a laundry pressing machine, a bed, 40 a conveyer arranged to travel intermittently over said bed, a pressing table located over said bed, means for reciprocating said table with relation to said bed for pressing articles carried by said conveyer, work stripping means, said means comprising a vertically movable work gripping member supported by and embracing the lateral edges of said table, and springs normally holding 45 said member depressed below the level of the table.

In testimony whereof I affix my signature in presence of two subscribing witnesses.

CARLOS A. SMITH.
